Inventor:

Charles O. Ellert

UNITED STATES PATENT OFFICE.

CHARLES O. ELLERT, OF BROOKLYN, NEW YORK.

SANITARY ATTACHMENT FOR TELEPHONE MOUTHPIECES.

Application filed July 5, 1922. Serial No. 572,954.

To all whom it may concern:

Be it known that I, CHARLES O. ELLERT, a citizen of the United States, and resident of the city of New York, borough of Brooklyn, county of Kings, and State of New York, have invented certain new and useful Improvements in Sanitary Attachments for Telephone Mouthpieces, of which the following is a full, clear, and exact 10 specification.

This invention relates primarily to one-piece sanitary attachments that may be easily attached to mouth-pieces for telephones, speaking tubes, or other like devices, and has for its object to attain by simple and erective construction, improved sanitary protection against infectious disease and germs often associated with unprotected telephone mouth-pieces.

Another object is to provide a sanitary attachment of suitable shape and size for telephone mouth-pieces, that may be made of paper, fiber, celluloid or like composition, or any other suitable material, that, if desired, may be readily discarded and replaced by a new sanitary attachment.

Another object is to provide a detachable and rotatable sanitary attachment for telephone mouth-pieces, adapted to brush, wipe and clean and disinfect said mouth-pieces, and the said sanitary attachment may be readily discarded when desired, and replaced by a new sanitary attachment.

Another object is to provide an improved sanitary cleansing and disinfecting attachment for telephone mouth-piece, which is simple in operation, cheap to manufacture, and which will act in an effective manner to prevent the said telephone mouth-pieces from serving as a carrier of infectious germs and diseases.

With these and other objects in view, the invention consists in the novel construction, combination and arrangement of parts as hereinafter described and claimed, reference being had to the accompanying drawings in which like reference characters refer to like parts throughout the several views.

Fig. 1 is a broken longitudinal section view of a telephone mouthpiece showing in cross section the invention as applied to said mouthpiece.

Fig. 2, is a view of the open end of said telephone mouth-piece showing the interior

member of the sanitary attachment mounted upon the said telephone mouthpiece. 55

Fig. 3, is an exterior view of the mouthpiece showing the exterior member of said sanitary attachment mounted upon said telephone mouth-piece. 60

Fig. 4, is a detail view, showing a modification in construction of the sanitary mouth-piece. 65

Fig. 5, shows an approximately shaped blank of a single piece of suitable material used in the construction of the sanitary attachment.

Fig. 6 shows an approximately formed attachment formed from a single piece blank as shown in Fig. 5, the dotted lines 70 indicating the portions B and B' suitably formed or molded to provide a suitable slot or channel opening of approximately the thickness of the wall of said telephone mouthpiece. 75

Fig. 7, is a detail view of a further modification in construction of the said sanitary attachment for telephone mouth-pieces.

Fig. 8, is a modification in construction of the sanitary attachment for telephone 80 mouthpieces, showing the exterior member provided with a bifurcated or forked end, and provided with a plurality of positioning means.

The sanitary attachment for telephone 85 mouth-pieces is made preferably from a suitable blank, approximately the shape and form shown in Fig. 5, and comprising a central portion A, having extensions or projections B, and C, thereon. 90

The said blank is made preferably of paper, fiber, celluloid or like composition, or any other suitable material, sufficient thickness being left, if desired, at the base A', of the projection B, to afford the necessary stiffness and resiliency in action. 95

The part B, is adapted to be bent or molded as indicated by dotted lines, Fig. 6, approximately parallel with the main body portion C. The ends B', C', are adapted to 100 define a suitable slot or opening of approximately the thickness of the wall of the said mouth-piece 1, and approximately shaped or molded to the contour lines of a segmental portion of said mouth-piece. Suitable 105 points, as indicated at 3, Fig. 1, 10, Fig. 4, on the main body portion C are adapted, if desired, to be made slightly thicker and,

heavier than the other portions of the main body C, for the purpose of mounting or positioning a suitable locking means, as 5, Fig. 1, 11, Fig. 4, whereby to detachably lock 5 said main body portion C, against accidental displacement when said sanitary attachment is detachably mounted on said telephone mouth-piece. If desired, the main body portion C, may be bifurcated or forked, and 10 a locking means suitably adapted to said member C.

As indicated in Fig. 1, and Fig. 4, a suitable locking means, including preferably, a screw threaded device 5, 11, having a suitable operating head 4, 9, is preferably positioned at points 3, 10, on the main body portion C. The operation of the said locking means is adapted to permit the adjustment of the friction pressure engagement of the 20 said sanitary attachment with the wall of the said mouth-piece.

As shown in Fig. 1, the screw threaded device 5, is adapted to have suitable engagement in direct contact at suitable points 25 as indicated at 6, on the wall of the said mouth-piece. The adjustment of the screw threaded device adjusts the pressure of the internal jaw upon the internal wall of the telephone mouthpiece.

30 In Fig. 4, a modification is shown, wherein a suitable friction member 14, preferably of rubber or other material, is suitably mounted as indicated at points 15, 16, upon a suitable end 13, of the main body C. The 35 opposite end of said member 14, adjacent points 14^a, is adapted to be pressed away from the main portion C, by a suitable end 12, of the screw threaded device 11, in a manner to permit a suitable pressure engagement of said member 14, with the wall of said mouth-piece, when desired, by the 40 operation of the said locking means.

In Fig. 7, is shown a still further modification in construction of the said improved 45 sanitary attachment wherein the main body portion C, at points near its end C³, is provided with a suitable locking means having a body portion E, adapted to be suitably secured to said main body portion C, by 50 suitable holding means, as riveting indicated by 18, 19, or in any suitable manner.

The extreme end F, of the said locking means is preferably adapted to be thicker than the main body portion E, and adapted 55 to suitably engage with a screw threaded device 11^a, passing through a suitable co-acting threaded opening in said end F, in a manner whereby a suitable end 11^b, suitably 60 engages with the wall of said mouth-piece 1. The construction of the locking means shown in Fig. 7, is preferably, to permit a spring actuated contact engagement with the wall of said mouth-piece 1, whereby any locking adjustment of the said screw device 65 11^a, provides a spring pressure upon the

said spring like member E, and tends to adjust the pressure of the internal jaw upon the internal wall of the telephone mouth piece.

The said sanitary attachment is firmly and detachably positioned against accidental displacement in position upon said mouth-piece, 1, and a slight releasing or adjustment of the screw threaded device, permits the sanitary attachment to be rotated or moved around the rim or periphery 1^a, making as many revolutions around the said rim 1^a, as desired, to brush and clean and disinfect the said mouth-piece and when desired, the said locking means is adapted to be adjusted to increase the holding pressure engagement of the said sanitary attachment against co-acting points upon the wall of said mouth-piece, and the said attachment is held securely against accidental displacement of its position upon said mouth-piece.

A suitable container means 17, 17^a, 17^b, Figs. 1, 4, and 7, respectively, is suitably adapted for containing suitable disinfectant elements or element, and is suitably mounted or positioned at points on the opposing inner faces of the said main body portion C, and the resilient arm B, whereby to form means adapted to clean and disinfect and render the said mouth-piece 1, in a sanitary condition and proof against infectious disease and germs.

A suitable container means, as 17, of felt, cloth or other suitable material, may be adapted to suitably engage points on the inner face of the interior resilient arm B, and co-acting points on the interior face of the wall of said mouth-piece. The said main body portion C, if desired, may be adapted with or without the said disinfectant container means 17^a, 17^b, to engage the said wall of said mouth-piece 1.

The said container means 17, 17^a, 17^b, are adapted to be suitably supplied with a suitable disinfectant element or elements, preferably in a dry form. The breathing of the party using the telephone mouth-piece supplies all the necessary moisture required to co-operate with said disinfectant elements to render said elements active. As a modification, a suitable element or elements may be applied as a coating or veneer or a varnish like element upon the inner face or surface of the said resilient arm B. Said coating or veneer is adapted to have disinfectant properties or power to disinfect said telephone mouth-piece.

Although the area or size of the said sanitary attachment covers or encloses only a segmental portion or area of the wall of the said mouth-piece, the slidable or rotatable movement of the said sanitary attachment when detachably mounted upon the said mouth-piece, easily and quickly permits said

sanitary attachment to render the entire mouth-piece in improved sanitary condition and safe from disease and germ infection resulting from telephone mouth-pieces being in an unsanitary condition.

It is readily seen that the construction herein shown and described, provides a sanitary attachment for telephone mouth-pieces having compactness and utility combined with effectiveness in form and color adapted to give the operator or user of said telephone mouthpiece, convenience, confidence, and increased safety from germ infection resulting from telephone mouthpieces being in an unsanitary condition.

The said sanitary attachment by reason of its construction and resiliency is easily and quickly mounted upon the said mouthpiece and is readily adapted to clean and disinfest the said mouthpiece, and readily permits a suitable brushing engagement to be directed against the wall or walls of said mouthpiece.

The said sanitary attachment on account of its resiliency and construction is quickly and readily detachably mounted upon said mouth-piece against accidental displacement, and it will be particularly noted that the said sanitary attachment may be mounted at any suitable point upon the rim 1^a, or periphery of the said mouth-piece, the said resilient arm B, functioning just as well from one point or side as from another.

While I have shown a preferred embodiment of the invention, it will be understood that the invention is not to be limited to exact details of construction herein shown and described, and change therein and modification thereof may be made within the scope of the appended claims without departing from the spirit of the invention or sacrificing any of its advantages.

Having described my invention, I claim:

1. A sanitary attachment for telephone mouthpieces, comprising a member formed from a single piece of material or element, and having a main body portion, a resilient jaw member in engagement with said main body portion, said resilient jaw member being adapted to engage with a disinfectant holding means, and a screw actuated means engaging said main body portion and said mouthpiece in a manner whereby said body portion is detachably locked against displacement upon the periphery of said telephone mouthpiece.

2. A sanitary attachment for telephone mouthpieces, comprising a clip having oppo-

sitely disposed resilient jaw members, means engaging said clip and adapted to support a disinfectant element or elements adjacent the wall or walls of said telephone mouthpiece, and a screw actuated means engaging said clip whereby said sanitary attachment is detachably locked against displacement upon the periphery of said telephone mouthpiece.

3. A sanitary attachment in the form of a clip, for telephone mouthpieces, said sanitary attachment including a member formed from a single piece of desirable material provided with a screw actuated means whereby said attachment is permitted to be rotatably adjusted and detachably locked against displacement upon the periphery of said telephone mouthpiece.

4. The combination with a telephone mouthpiece, of a member adapted to position a disinfectant element or elements adjacent the wall or walls of said telephone mouthpiece, and a screw actuated means carried by said member whereby said member is rotatably adjusted and detachably locked against displacement upon the periphery of said telephone mouthpiece.

5. A sanitary attachment for telephone mouthpieces, comprising a clip having internal and external jaw members, means to support a disinfectant element or elements adjacent the wall or walls of said telephone mouthpiece, a bifurcated end provided on said external member, and a plurality of screw actuated means engaging said bifurcated end whereby said attachment is rotatably adjusted and detachably locked against displacement upon the periphery of said telephone mouthpiece.

6. A sanitary attachment for telephone mouthpieces, comprising a clip having internal and external portions, means to support a disinfectant element or elements adjacent the wall or walls of said telephone mouthpiece, and positioning means, including screw actuated means engaging said sanitary attachment and said mouthpiece whereby said sanitary attachment is rotatably adjusted and positioned against displacement upon the periphery of said telephone mouthpiece.

In testimony whereof, I have signed my name.

CHARLES O. ELLERT.
